(57) CLAIM

The ornamental design for a detergent pouch, as shown and described.

DESCRIPTION

FIG. 1 is a first perspective view of a detergent pouch showing my new design;

FIG. 2 is a second perspective view thereof;

FIG. 3 is a top view thereof;

FIG. 4 is a bottom view thereof;

FIG. 5 is a front view thereof;

FIG. 6 is a side view thereof;

FIG. 7 is a third perspective view thereof;

FIG. 8 is a first perspective view of a second embodiment of the design of a detergent pouch;

FIG. 9 is a second perspective view thereof;

FIG. 10 is a top view thereof;

FIG. 11 is a bottom view thereof;

FIG. 12 is a front view thereof;

FIG. 13 is a side perspective view thereof; and,

FIG. 14 is a third perspective view thereof.

The back or rear view is identical to the front views shown in FIGS. 5 and 12. The right side is identical to the left side views shown in FIGS. 6 and 13. The gray color in FIGS. 8-14 is included as shading to illustrate a color contrast in appearance of the detergent pouch, but the gray color forms no part of the claimed design.
